RUBBER HEEL

Ralph A. Hyde, Brookline, Mass.

Application May 10, 1957, Serial No. 46,101

Term of patent 14 years

(Cl. D7—5)

Fig. 1

The sides of the heel are plain. The top face of the heel is conventional.

I claim:

The ornamental design for a rubber heel, as shown and described.
